(57) **CLAIM**

We claim the ornamental design for a shelving bracket, as shown and described.

DESCRIPTION

FIG. 1 is a perspective view of the shelving bracket embodying the present invention;

FIG. 2 is a rear elevational view of the shelving bracket shown in FIG. 1;

FIG. 3 is a front elevational view of the shelving bracket shown in FIG. 1;

FIG. 4 is a top plan view of the shelving unit shown in FIG. 1; FIG. 5 is a bottom plan view of the shelving bracket shown in FIG. 1;

FIG. 6 is a first side elevational view of the shelving bracket shown in FIG. 1; and,

FIG. 7 is a second side elevational view the shelving bracket shown in FIG. 1.

Dashed lines and broken lines are for the purposes of illustrating environmental structure, and form no part of the claimed design.
